Federal Ceramics Corporation, Mineral City, Ohio, a corporation of Ohio

Filed Apr. 16, 1962, Ser. No. 69,721

Term of patent 14 years

(Cl. D4—3)

FIG. 1 is an isometric view of a toilet paper holder embodying my new design;

FIG. 2 is a top plan view thereof;

FIG. 3 is a front elevational view thereof;

FIG. 4 is a side elevational view thereof;

FIG. 5 is a rear elevational view on a reduced scale.

The side not shown is like the side shown.

The dominant features of my design reside in the portions shown in full lines.

I claim:

The ornamental design for a toilet paper holder, as shown and described.
